UNITED STATES PATENT OFFICE.

JOSEPH E. WOOD, OF CHICAGO, ILLINOIS, ASSIGNOR OF ONE-FOURTH TO CHARLES A. TERREL AND ONE-EIGHTH TO ALICE M. WAGNER, BOTH OF CHICAGO, ILLINOIS.

SIGNAL LIGHT.

Application filed February 19, 1926. Serial No. 89,348.

My invention relates to improvements in signal lights, and it consists in the combinations, constructions, and arrangements herein described and claimed.

An object of my invention is to provide a signal light which is especially adapted for vehicles, but which can be used at street corners, building exits, etc.

A further object of my invention is to provide a device of the type described which takes the place of a tail light, a stop light, and parking lights, and which has novel means for changing from a clear signal to a warning signal.

A further object of my invention is to provide a device of the type described which is thoroughly efficient and durable for the purpose intended.

Other objects and advantages will appear in the following specification, and the novel features of the invention will be particularly pointed out in the appended claims.

My invention is illustrated in the accompanying drawings, forming part of this application, in which—

Figure 1 is a side elevation of the device as applied to a vehicle.

Figure 2 is a front elevation of the device in normal position.

Figure 3 is a front elevation of the device showing the stop signal.

Figure 4 is a section along the line 4—4 of Figure 2.

Figure 5 is a fragmentary view of the device.

Figure 6 is a section along the line 6—6 of Figure 4.

Figure 7 is a plan view of a portion of the device, and

Figure 8 is a wiring diagram.

In carrying out my invention, I provide a cup-shaped casing 1 mounted upon a suitable support, such as the chassis 2, by means of a bracket 3. The casing 1 is provided with lugs 4 upon which a movable disc 5 is placed. The movable disc 5 has a relatively large opening 6 therein and a plurality of smaller openings 7 and 8 disposed around the opening 6. A relatively large red lens 9 is placed within the opening 6 and smaller red lenses 10 are placed within the openings 7. A plurality of green lenses 11 are placed within the openings 8. The disc 5 is spaced away from the casing 1 by means of leaf springs 12. A socket 13 is secured to the

inner wall of the casing 1 and contains a bulb 14 disposed back of the lens 9 near the center of the casing.

The casing is provided with an annular flange 15. A cover plate 16 is disposed within the casing adjacent the disc 5, its peripheral edge resting upon the flange 15. The cover plate 16 is preferably made of glass having an opaque sheet 17 secured to one surface thereof. The sheet 17 is provided with a large opening 18 and smaller openings 19. The cover plate 16 is held within the casing 1 by means of a clamp 20 and is prevented from rotative movement by means of a bur 21.

The disc 5 is positioned within the casing 1 in such a manner that one green lens will be at the top, another at the bottom, and one at each side thereof. The disc is held in this position by means of a tension spring 22, one end of which is secured to the disc at 23 and to the lug 4', as shown in Figure 6. The disc 5 is limited in its movement by a projection 24. The means for moving the disc consists of a wire 25 secured at one end to the disc, as at 26, and at the other end to a tension spring 27. The free end of the tension spring 27 is secured to the brake rod 28. The brake rod 28 is operatively connected to the brake pedal 29.

The casing 1 is provided with an opening 30 through which rays of light may be projected upon a license plate, not shown. A pair of lenses are placed one on each side of the casing 1 and rigidly secured thereto. The purpose of these lenses is to serve as parking lights.

From the foregoing description of the various parts of the device, the operation thereof may be readily understood. In Figure 8, I have shown a wiring diagram. I have shown a source of current, as at B, a switch S, and a conductor C. When the device is applied to a vehicle, the current flows from the source of current through a wire 31, through the switch S, when closed, through a wire 32, and through the light 14 back to the source of current B. This shows the path of the current when the device is used on a vehicle at night.

At night, the circuit is closed to continuously project rays of light through the lens 9, constituting a stop light, and through the lenses 11, constituting clear signals. In the daytime, however, the tail light is not

needed and the switch S is opened, thus breaking the circuit. The purpose of the device in the day-time is to flash a warning signal when the driver of the vehicle 5 intends to stop or slow down. The means for closing the circuit for flashing a warning signal at any desired time consists in the pressing down of the brake pedal 29, the lower end thereof contacting with the 10 conductor C, thus closing the circuit.

The purpose of the lens 9 is to constitute a tail light when the circuit is closed. The lenses 11 constitute a clear signal when the circuit is closed. By the word "clear" I 15 mean that the traffic or the right-of-way is clear ahead. The lenses 10, upon which I have shown the letters "S T O P", constitute a warning signal when the circuit is closed. It will be observed that the green 20 lenses are normally in alignment with the openings 19. The device therefore, when the circuit is closed, normally indicates a clear signal. When the driver of the vehicle upon which the device is applied intends to stop 25 or slow down, he naturally presses down upon the brake pedal 29, and in doing so, the wire 25 is pulled downwardly. In the movement of the wire downwardly, the disc 5 is rotated in the direction of the arrow 30 33 until the projection 24 strikes the lug 4^a. In this movement, the clear lenses are hidden behind the cover plate 16, and the lenses 10 are brought in alignment with the openings 19. The disc is held in this position until 35 the brake pedal 29 is released. The disc 5 will again be returned to normal position by means of the tension spring 22. The purpose of the springs 12 is to allow the disc 5 to move easily, and to prevent it from rattling. At the lower portion of the casing 1, I have shown an opening for the purpose of 40 allowing rays of light to project upon a license plate, or the like.

It will be observed that the device can be 45 used upon street corners for indicating the traffic to stop or go. When the device is so used, the switch S is constantly closed, the device normally indicating a clear signal. When it is desired to flash a stop signal, the 50 wire 25 is pulled downwardly, thus swinging the green lens in back of the cover plate and the red lens in alignment with the openings 19.

I claim:

55 1. A device of the type described comprising a casing having a source of light disposed therein, a disc, clear signals disposed in said disc, warning signals disposed between said clear signals in said disc, a cover 60 plate disposed adjacent to said disc normally allowing the rays of light to project clear signals therethrough and to hide the warning signal, and means for automatically moving said disc, whereby the clear signals

will be hidden by said cover plate, thus allowing the rays of light to project warning signals therethrough. 65

2. A device of the type described comprising a casing having a source of light disposed therein, a disc containing a lens constituting a tail light, a lens constituting a clear signal, and a lens constituting a warning signal, means for continuously projecting rays of light through said first and said 70 second named lenses, and means for automatically moving said disc for causing the rays of light to project through said third named lens and not said second named lens. 75

3. A device of the type described comprising a casing having a source of light disposed therein, a disc, clear signals disposed in said disc, warning signals disposed between said clear signals in said disc, a colored lens constituting a tail light carried by said disc, a cover plate disposed adjacent to said disc normally allowing the rays of light to project clear signals therethrough and to hide the warning signals, said plate allowing the rays of light to project through said colored lens, and means for automatically moving said disc, whereby the clear signals will be hidden by said plate, thus allowing the rays of light to project warning signals therethrough. 80

4. A device of the type described comprising a casing having a source of light disposed therein, a disc having clear and warning signals disposed therein, a colored lens constituting a tail light carried by said disc, a cover plate disposed adjacent to said disc normally allowing the rays of light to project clear signals therethrough and to hide the warning signals, said plate allowing the rays of light to project through said colored lens, means for automatically moving said disc, whereby the clear signals will be hidden by said plate, thus allowing the rays of light to project warning signals therethrough, and means for returning said disc 90 to normal position. 95

5. A device of the type described comprising a casing having a source of light disposed therein, a disc, clear signals disposed in a circuitous path in said disc, warning signals disposed between each of said clear signals, a colored lens constituting a tail light disposed in the center of said disc, a cover plate disposed adjacent said disc normally allowing the rays of light to project clear signals therethrough and to hide the 100 warning signals, said plate allowing the rays of light to project through said colored lens, and means for automatically moving said disc, whereby the clear signals will be hidden by said plate, thus allowing the rays of light to project warning signals therethrough, and means for returning said disc 105 to normal position. 110
